ATTORNEY

UNITED STATES PATENT OFFICE.

PERCY L. HILL, DECEASED, LATE OF NEW YORK, N. Y.; BY JAMES W. ANDERSON,
ADMINISTRATOR, OF NEW YORK, N. Y.

PROCESS FOR MAKING CHARACTER CARRIERS FOR COMPOSING MACHINES.

Original application filed August 12, 1919, Serial No. 317,044. Divided and this application filed
February 5, 1923. Serial No. 617,030.

To all whom it may concern:

Be it known that PERCY L. HILL, formerly a citizen of the United States, residing in New York, in the county of New York and 5 State of New York, but now deceased, did during his lifetime invent certain new and useful Improvements in Processes for Making Character Carriers for Composing Machines, of which the following is a full, clear, 10 and exact description, such as will enable others skilled in the art to which it appertains to make and use the same.

This invention relates to composing machines, such as the linotype, the intertype, 15 and other machines where the character carrying elements are provided with indicating characters for the guidance of the operator, etc., and with respect to its more specific features to the character carrying element for 20 such machines as, for instance, exemplified in that of the linotype machine, and others involving line casting operations.

One of the objects of the invention is the provision of a simple and practical process 25 for treating the reference faces of the character carrying elements so as to more readily permit the reading of the characters on such faces and eliminate eye strain heretofore resulting to the composing machine operator 30 when viewing the assembled characters under usual operative conditions.

Another object of the invention is the provision of a process of the character referred to and wherewith the reference faces of the 35 character carrying elements are placed in a condition for quick and accurate deciphering of any reference character or of a line of such characters thereby increasing the output of the composing machine under 40 usual operative conditions.

Other objects will be in part obvious and in part pointed out hereinafter.

The invention accordingly comprises the several steps and the relation and order of 45 one or more of such steps with respect to each of the others thereof, which will be exemplified in the process hereinafter disclosed, and the scope of the application of which will be indicated in the claims.

In the accompanying drawing forming 50 part of this specification and wherein similar reference characters refer to similar parts throughout the several views,

Figure 1 is a perspective view of a character carrying element, the reference face 55 of which has been treated in accordance with the process;

Fig. 2 is a side view of Fig. 1 showing the opposite side; and

Fig. 3 is a sectional detail of a portion of 60 the character carrying element.

For the purpose of disclosing the invention, there is illustrated a character carrying element, or carrier, 1, such as is ordinarily employed in a linotype machine, but 65 treated in accordance with the present process. This element is provided with the usual appurtenances which cooperate in the machine to select and deliver it to the type casting operation and to distribute it after 70 casting. It is to be understood, however, that the invention is adapted for other types of composing machine and for character carrying elements of different kinds.

The numeral 2 indicates one edge of the 75 carrier, 1, on which is a "character", such as a letter, numeral, or other sign to be reproduced in the composition. On the opposite edge of the carrier is another "character", indicated by the numeral 3, being, 80 in the present instance, the letter "H", which indicates to the operator that the character on the opposite edge is also the letter "H". The foundation of the carrier, 1, may be of brass or other metal, and the indicating 85 character, 3, is impressed therein, as by being sunk, or made "intaglio", in its edge.

The operators of composing machines of the kind referred to work under conditions which not only render it difficult to read the 90 indicating characters of the carriers, but cause severe eye strain, due to the constant attention required in reading for long periods of time under poor lighting conditions, most of the work being done under 95 electric light. The character carrying elements of a composing machine as, for instance, the matrix or matte of the linotype

machine, are light colored, being usually made of brass or other composition of a yellowish color capable of a high polish. The usual indicating character on the reference face 4 of the character carrying element is merely a properly shaped recess in the edge of the carrier, the recess being an indentation in the reference face and consequently of the same color as the surrounding surface. 5
10 In consequence both the indicating character and the surrounding surface of the reference face are of the same color and the indicating character may only be visibly distinguished with difficulty. In use, the indented indicating characters become filled with dust, grease, and the like so that in the majority of instances as time passes it becomes even more difficult to visibly distinguish the indicating character and increased eye strain in the effort to distinguish 15 the indicating character results. When it is remembered that the positioning of an improper character in a single line in a linotype machine requires the recasting of the entire line, the increased efficiency by reason of any elimination of tendency to error in this regard is apparent. In accordance with the present invention the indented indicating character, 3, is made to contrast 20 sharply in color with the surrounding surface or field, 4, of the reference face, and the light reflecting quality of the surrounding surface 4 is reduced so that the rays from this source do not impair the clear 25 view of the indicating character as, for instance, by dazzling the sight. According to the present invention the reference face is colored to make it dark, and the indicating character is given a lighter color sharply contrasting with the dark surrounding field. 30 Black and white, respectively, are suitable contrasting colors. The indicating character may be filled in with a white paint or pigment. This coloring matter preferably 35 fills the indented character flush with the surface in which it lies, as illustrated in Fig. 3, which shows a section of a portion of the carrier, 1, transversely of the cross line 5 in the letter "H". 40
45 The surface, 4, is treated to color it black as, for instance, by a suitable chemical or oxidizing agent which will color the brass black. In practice the reference face, 4, and the intended indicating character therein 50 may first be colored black by the chemicals and thereafter the white filling applied to the indicating character over the black surface thereof. Thus on viewing the matrix the relatively small indicating character, 3, will be seen sharply contrasting in color with 55 the field, 4.
60 Furthermore not only is the reference face of the carrier colored, as described, but its light reflecting quality is reduced relative to 65 that of the brassy surface of the carrier and

also reduced relative to that of the treated or white indicating character, 3. It is found that treatment of the surface, 4, as, for instance, by oxidizing said surface to make it black, also results in reducing or deadening 70 its light reflecting quality. In consequence the white indicating character, 3, is viewed in bold relief against the much darker surrounding field and it will be noted that although the indicating character is white, 75 and has consequently a high light reflecting quality, its area is relatively small and not adapted under operative conditions to reflect light in such amounts as to interfere with the clear view of this character. On 80 the other hand, the area of the surrounding surface is relatively large so that a great amount of light would be reflected from this surface and interfere with the operator's view of the indicating character, were it not 85 for the fact that the light reflecting quality of this surface is of a subdued character and preferably deadened. A surface for the field, 4, having the subdued light reflecting quality of a carbon coated surface would be 90 desirable, although an unpolished, darkened surface, as obtained by the treatment hereinbefore referred to, answers the purpose in a highly efficient manner.
95

The coloring for the field and for the indicating character should be as permanent as possible, and the filling for the indicating character should be such as to be firmly retained in place.

Since certain changes may be made in 100 carrying out the above process without departing from the scope of the invention, it is intended that all matter contained in the above description shall be interpreted as 105 illustrative and not in a limiting sense.

It is also to be understood that the following claims are intended to cover all of the generic and specific features of the invention herein described, and all statements of the scope of the invention which, as a matter of language, might be said to fall therebetween.
110

The present application is a division of the application of Percy L. Hill filed 115 August 12, 1919, Serial No. 317,044.

Having described my invention, what I claim as new and desire to secure by Letters Patent is:—

1. The process of coloring a light colored metallic matrix adapted for line casting machines and having on its edge an indented indicating character, said process including treating said edge including said indicating character to make the same dark or black and thereafter filling in the indented indicating character with a lighter colored or white pigment.
120

2. The process of coloring a light colored metallic matrix adapted for line casting machines and having on its edge an indented 125

130

indicating character, said process including
treating said edge including said indicating
character to deaden the light reflecting
quality thereof and also to make the same
5 dark or black, and thereafter filling in the
indented indicating character with a pigment
of high light reflecting quality and
contrasting sharply in color with the re-
sultant treated edge.

In testimony whereof I affix my signature, 10
in the presence of two witnesses.

JAMES W. ANDERSON,
Administrator of the estate of Percy L.
Hill, deceased.
